UNITED STATES PATENT OFFICE.

FRED H. DANIELS, OF WORCESTER, MASSACHUSETTS.

MECHANISM FOR FORMING INGOTS, BARS, RODS, &c., FROM FLUID METAL.

SPECIFICATION forming part of Letters Patent No. 359,348, dated March 15, 1867.

Application filed June 4, 1866. Serial No. 204,115. (No model.)

To all whom it may concern:

Be it known that I, FRED H. DANIELS, a citizen of the United States, residing at Worcester, in the county of Worcester and State of Massachusetts, have invented certain new and useful Improvements in Mechanism for Forming Ingots, Bars, or Rods from Fluid Metal, of which the following, together with the accompanying drawings, is a specification sufficiently full, clear, and exact to enable persons skilled in the art to which this invention appertains to make and use the same.

The object of this my present invention is to provide an efficient and practical mechanism for forming continuous ingots from fluid metal, which mechanism affords a continuously-traveling mold or receiving-space into which the metal can be introduced in a continuous molten or fluid stream, and wherein said metal is confined and supported until it has congealed or become solid, while constantly advancing toward a point of delivery at which the ingot is discharged in a constantly-increasing length and in a sufficiently cool and solid condition to be handled, rolled, or subjected to such usage as may be required in subsequent process of treatment; also, to provide facilities for controlling and regulating the flow of fluid metal to the constantly-advancing ingot-forming mold during the operation of casting the ingot, in order that the proper quantity of metal may be supplied to completely fill the mold without permitting overflow or waste of metal in the operation; also, to afford facilities for regulating the tension of the flexible exterior portion of the mold, and for holding it in connection with the curved surface of the matrix support or wheel to afford facilities for cooling the matrix; also, to provide means, in combination with the mechanism for forming ingots from fluid metal, whereby fins or roughness at the angles of the ingot can be removed as the ingot is delivered from the forming-matrix. These objects I attain by mechanism the nature, construction, and operation of which are illustrated in the drawings, and hereinafter explained, the particular subject claimed being hereinafter definitely specified.

In the drawings, Figure 1 is a view, in sectional elevation, illustrating my improvements

in mechanism for making ingots from fluid metal. Fig. 2 is a plan view of the same, the upper part being removed to reveal parts beneath. Figs. 3, 4, and 5 are sections through the traveling mold, showing different modifications in the construction of the wheel and shape of the matrix and ingot. Fig. 6 shows a detail view of the shear device for removing fins from the angles of the ingot. Fig. 7 is a detail view of grinding-wheels for dressing the angles of the ingot. Fig. 8 is a view of a portion of the flexible exterior or cover of the mold or matrix constructed as a series of linked plates, or in the manner of a chain. Fig. 9 is a transverse section showing the rim of the matrix-wheel, a chain-band, and a water-back. Fig. 10 is a section of the rim of the matrix-wheel, showing a partition or rib for separating the ingot at definite intervals. Fig. 11 is a vertical longitudinal sectional view showing the delivery-guide on a larger scale, and Fig. 12 is a transverse vertical section of said guide.

In referring to parts, A denotes a large circular wheel or matrix-carrier, revoluble on a central axis or shaft supported by suitable bearings on the frame B and adapted to receive motion from a driving engine or motor (not shown) connected with the axial shaft a. The face or rim of the wheel A is dressed off true and smooth, and is provided with a channel, depression, or groove, C, of a size and shape corresponding to that required for the ingot, which groove extends around the wheel and forms the matrix or continuous mold into which the fluid metal is cast.

The ingot may be made in any form of section, but I prefer one of the forms shown in Figs. 3, 4, and 5—viz., a square, a triangular, or a half-round shape—as such forms will leave the matrix or groove more readily at the point of discharge.

D indicates the flexible exterior portion of the mold, consisting of an endless band supported in contact with the face of the wheel A by means of guiding-wheels E E', the axial journals of which are arranged to turn in suitable bearings on the upper and lower part of the frame, respectively. Said wheels serve to keep the band D firmly drawn against the curved surface of the wheel A and cause it to move in unison therewith, so there will be no

sliding friction between the parts or against the surface of the ingot while being produced. A tension and guiding wheel, E', is arranged for the rear part of the band. The journal bearing boxes E', in which the axis or shaft of said wheel E' is mounted, are made adjustable in the frame B, and are provided with screws e, as indicated, or equivalent means whereby said wheel can be moved for increasing or decreasing the tension of the band D.

The wheels E E' are operated by gears E', that mesh with a gear, A', connected with the main wheel A or its shaft. The wheels A, E, and E' are provided with peripheral flanges, 15 to retain the band D in proper alignment with the face of the wheels and matrix C.

The band D is preferably formed of a strip of sheet-steel, copper, or other suitable material of proper width and having sufficient flexibility to work over the guide pulleys or wheels and to lie up close to the face of the mold. In some instances, if desired, a chain of linked plates may be employed in lieu of the metal-ribbon band, said plates being curved to fit 25 the face of the wheel and hinged together at their ends, so that the successive plates match closely against each other when brought into position for closing the matrix.

Another modification in construction which 30 may be employed is to use the band D, or a thin facing band or ribbon of sheet metal, in connection with a re-enforce or backing band, D', formed of chain links or plates hinged together at their ends, as indicated in Fig. 8. In 35 this case the facing-band and the backing-chain could be carried either on the same or separate guiding wheels or pulleys, the chain D' rotating within the circuit of the facing-band D and moving into position to take bearing against said band D, where the latter is brought against the face of the matrix-wheel A, and the two then moving in unison with said wheel to the position of discharge.

If desired, a series of rolls, d', may be arranged at the back of the chain or band, for 45 pressing it up to the face of the wheel, as indicated by dotted lines in Fig. 8.

F indicates a cooler or water-casing, having an internal water-space, W, arranged on the 50 back of the band D, along the space between the rolls E and E', for the purpose of maintaining a current of water along the exterior surface of said band above the matrix, for cooling and congealing the fluid metal in the matrix. 55 A water-supply pipe, f, connects with the upper part, and openings T are formed at the bottom of the casing to permit the water to escape.

F' indicates adjusting screws or devices for 60 supporting the casing F and pressing it forward against the band with the desired force.

G indicates the ladle or hopper located at the 65 upper part of the frame and adapted for containing the supply of molten metal to be fed to the mold. Said ladle is furnished with an opening in its bottom from which the metal can flow into the guide-funnel h, whereby it is

directed into the channel or matrix C. A stopper, H, having suitable operating devices, as H', serves for regulating the flow of metal 70 as required.

K indicates a ladle connected with a crane, K', for transferring fluid metal from any suitable melting-furnace to replenish the supply in the ladle G as required.

P P' indicate platforms for the workmen to stand upon while attending the ladles.

S indicates a rotary shear for trimming off fins or projections, in case any should be formed along the angles of the ingot, should 80 the metal at any place be forced out between the band and face of the wheel. Said shear consists of disks or rotary cutters mounted on shafts s s', respectively, above and below the line of the ingot, the edges of the disks being 85 fitted to shear against each other as the disks are rotated at suitable speed by means of gearing t driven from the main gear of the machine, or in other suitable manner. Said shear is preferably located adjacent to the delivery-guide L, whereby the congealed ingot is discharged from the forming matrix or groove C and directed outward upon a receiving-platform or roller-bed, M, which latter may extend any desired distance from the foot of the 95 ingot-forming mill.

The guide L is made with a removable top section, L', the front end of which is formed as a wedge or scraper for forcing the ingot I from the matrix or groove C, straightening the 100 curvature and directing the same away from the wheel tangentially to the circle of the circumference thereof in the manner indicated. The top of the guide, L', is held in place by a cross-bar, l, and key l', which bar is made of 105 sufficient strength to withstand all normal strain, but weak enough to break in case any extraordinary strain is brought upon the guide, so that in case of the choking of the ingot or other derangement the top of the 110 guide will come off and relieve the mechanism from damage.

The guide may be extended to any length desired, so that in case the interior of the ingot is in fluid condition when it reaches said 115 guide the guide will support it and facilitate the further cooling or complete congealing of the metal before it is released therefrom. For more rapidly effecting this action the guide is preferably made with openings e, as indicated 120 in Figs. 11 and 12, through it, and a constant flood or stream of water is directed upon the guide and ingot passing through it from a suitably-disposed water-supply pipe, O, or in other equivalent manner, the perforations 125 permitting the access of the water or cooling-fluid directly to the surface of the ingot.

N denotes grinding-wheels, of emery or other suitable material, disposed in a manner to act upon the angles or edges of the ingot 130 for smoothing off projections and excrescences as the ingot runs out upon the table M. Said wheels are provided with suitable gearing, n, or means for effecting their rotation, operated

in connection with the main part of the mill or other driving power.

If it is desired to separate the ingot into bars or lengths, instead of delivering it in a continuous length, small lugs or projections V (see Fig. 8) may be attached to the band D, which projections enter the groove C and serve as partitions to cut off the matrix-space, or so nearly cut off said space that the ingot will 10 break apart at positions corresponding therewith as it becomes straightened by the guides or when cooled. In some instances partitions V' can be fixed in the groove C of the wheel A, if desired, as indicated in Fig. 10.

15 If desired, the rim of the wheel A may be formed hollow, as indicated at W', (see Fig. 5 and dotted lines, Fig. 11,) said hollow to be connected with passages through the arms and central shaft, and adapted to serve as a pass- 20 way for water or other refrigerating liquid to assist the cooling of the metal.

The operation of my improved ingot-mill is as follows: The metal, which may be melted, treated, converted, or prepared in any desired 25 manner in any suitable melting or producing furnace, is, as required, deposited in the hopper or ladle G, the mill then being put into operation, so that the matrix-wheel A and band D have a forward movement in the direction indicated. The attendant then raises the stopper H and allows the fluid metal to 30 flow into the matrix or groove C through the funnel h, a plug of fire-clay having been previously inserted in the groove C to prevent the 35 metal from escaping at the start, the stream being graduated to correspond with the movement of the traveling mold, so that the metal will fill the mold as fast as it advances, and without flowing over at the top. The metal is 40 held within the matrix by the band or flexible front portion, D, and as it descends by the forward movement of the parts it becomes congealed or solidified, so that as it reaches the lower side of the wheel, or the position where 45 the guide L is located, it has become sufficiently solid to retain its shape and to be transferred from the matrix to the guide, wherein it is further cooled, as hereinbefore stated, and passes out upon the roller-table M 50 in a continuous ingot or series of successive sections, or if the partitions V or V' are used in the matrix-groove, then in a series of defined lengths.

The band D and wheel A form a continuously-traveling mold, the parts of which advance and take place in conjunction with each other at the point of receiving the metal, move in unison, and support the metal while it is becoming congealed, and recede and open the 60 matrix at the point where the congealed ingot is discharged or transferred to the guides L, thus offering no sliding friction or resistance on the surface of the ingot until it has become sufficiently solid to withstand abrasive action.

65 I am aware that wheels having a matrix-groove in the peripheral face thereof have heretofore been described and shown in mech-

anism for producing continuous bars and rods from melted or fluid metal, and I do not therefore herein make claim, broadly, to such a wheel, irrespective of its combination with other parts.

What I claim as my invention, and desire to secure by Letters Patent, is—

1. In an apparatus for the continuous production of ingots, bars, or rods from molten or fluid metal, the combination of the revolvable wheel having a groove or matrix, an endless traveling band a portion of which embraces a segment of the peripheral circle of 75 said wheel, guide-pulleys for supporting and guiding said band against the periphery of said wheel, a tension-wheel, as E, mounted in journal-boxes which are movable in guide-ways in the supporting frame, and adjusting- 80 screws, whereby said boxes and the tension-wheel can be adjusted for regulating the tension of said band, substantially as and for the purpose set forth.

2. In an apparatus for the continuous production of ingots, bars, or rods from molten or fluid metal, the combination of the revolvable wheel having a groove or matrix in its 90 face, an endless traveling band working in conjunction therewith about a segment of the 95 surface, guide-pulleys for supporting and guiding said band, a water casing or cooler embracing said band along that portion adjacent to the face of the wheel, guides for discharging the ingot from the groove or matrix, 100 and means for delivering water upon said discharge-guide, substantially as set forth.

3. An apparatus for the continuous production of ingots, bars, or rods from fluid metal, constructed as herein illustrated and 105 described, consisting of the wheel having the peripheral matrix-groove revolvable in a vertical plane, the endless traveling band embracing a segment of the peripheral surface 110 of said wheel, the guiding and tension pulleys E E' E'', gears A' and B' for operating said wheel and band in unison, the ladle G, having the adjustable stopper H, the discharging and supporting guide L, edge-trimming devices S, and roller-bed M, arranged and operating substantially as set forth.

4. The combination, with mechanism for casting or producing ingots, bars, or rods from fluid metal, of shearing devices operating in connection therewith and adapted for cutting 120 off fins or projections from the ingot or bar as it is delivered from the forming-mill.

5. The combination, with mechanism for casting or producing ingots, bars, or rods from fluid metal, of a grinding mechanism for dressing off the edges of the ingot as it is delivered 125 from the forming mechanism, substantially as set forth.

6. The combination, with the band or chain D, of a projection V, adapted to enter the 130 matrix for separating the ingot into bars of definite length, as set forth.

7. The combination of a revolvable wheel, an endless band or chain working in conjunc-

tion therewith to form a traveling mold into which the metal is cast, and a water-casing enclosing said band, substantially as and for the purposes set forth.

5. The combination, with a traveling mold for forming ingots or bars, of a discharging-guide having a removable top section adapted to act as a wedge or scraper for forcing the ingot from the forming-matrix, and retained in position by a breaking-bar, *l*, and key, substantially as and for the purpose set forth.

9. The combination, with a traveling mold for forming ingots or bars from fluid metal, of a guide through which the ingot passes after 15 leaving the mold, adapted for straightening and supporting the ingot and maintaining the sectional form thereof while cooling and until perfectly congealed.

10. The combination of a traveling mold for forming ingots or bars from fluid metal by a continuous process, and a guide through which the ingot or bar is conducted as it leaves the forming-matrix, adapted for supporting the ingot and maintaining its sectional form, and provided with a series of openings through 25 which water or other fluid can have access directly to the surface of the metal for accelerating the congealing action of the interior, substantially as hereinbefore set forth.

Witness my hand this 31st day of May, A. D. 30
1886.

FRED H. DANIELS.
